[57] CLAIM

The ornamental design for a combined rechargeable flashlight and charger therefor, as shown and described.

DESCRIPTION

FIG. 1 is a top, front and left side perspective view of a combined rechargeable flashlight and charger therefor embodying my new design.

FIG. 2 is a top, rear and right side perspective view thereof.

FIG. 3 is a front elevational view thereof on an enlarged scale.

FIG. 4 is a rear elevational view thereof on an enlarged scale.

FIG. 5 is a top plan view thereof on an enlarged scale.

FIG. 6 is a bottom plan view thereof on an enlarged scale.

FIG. 7 is a left side elevational view thereof on an enlarged scale.

FIG. 8 is a right side elevational view thereof, on an enlarged scale.

FIG. 9 is an exploded perspective view thereof showing the flashlight separated from the charger.

FIG. 1FIG. 2FIG. 3FIG. 4FIG. 5FIG. 6FIG. 7FIG. 8FIG. 9
